UNITED STATES PATENT OFFICE

JULIUS A. MAHR, OF MINNEAPOLIS, MINNESOTA, ASSIGNOR TO INVENTORS' PATENT HOLDING COMPANY, OF MINNEAPOLIS, MINNESOTA, A CORPORATION OF SOUTH DAKOTA

BODY FOR FOLDING BABY CARRIAGES

Original application filed December 12, 1928, Serial No. 325,411. Divided and this application filed November 6, 1929. Serial No. 405,116.

My present invention has for its object the provision of a collapsible flexible body especially intended for embodiment in a folding baby carriage but also well adapted for use in automobiles where the same may be suspended from a relatively fixed part thereof.

Said invention is a division of my copending application entitled "Folding baby carriage", filed December 12, 1928, under Serial No. 325,411.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a side elevation of a folding baby carriage having the invention embodied therein, some parts being broken away and other parts being sectioned;

Fig. 2 a view partly in front end elevation and partly in transverse vertical section taken on the line 2—2 of Fig. 1;

Fig. 3 is a fragmentary detail view in section taken on the irregular line 3—3 of Fig. 1, on an enlarged scale;

Fig. 4 is a fragmentary plan view of the right side of the body and connected back support;

Fig. 5 is a fragmentary detail view with some parts sectioned on the line 5—5 of Fig. 4;

Fig. 6 is a fragmentary detail view with some parts sectioned on the line 6—6 of Fig. 1, on an enlarged scale; and

Fig. 7 is a detailed view principally in section taken on the line 7—7 of Fig. 6.

The numeral 8 indicates as an entirety the chassis of a folding baby carriage disclosed and broadly claimed in the application heretofore identified with the exception of the side bars 9 and folding body supports 10 at the ends of said chassis.

Referring now in detail to the present invention the numeral 11 indicates a collapsible flexible body made from any suitable material held to form by upper and lower tubular

metallic frame members 12 and 13, respectively, the former of which has on its under side and the latter of which has on its inner side longitudinal slots 14 and 15, respectively. Each frame member 12 and 13 and its slots 14 and 15, respectively, is in endless arrangement and the ends of said members are connected, as will hereinafter appear.

The body 11 is attached to the frame member 12 by having its upper edge portion, which extends through the slot 14, folded around a flexible core 16 in said member and secured thereto by stitches or other fastening means 17. The frame member 13 is secured to the lower edge portion of the body 11, which extends into said body through its slot 15, by a flexible core 18, similar to the core 16, and which core 18 is secured to the body 11 by fastening means 19 similar to the fastening means 17.

A flexible apron 20 forming a depending extension of the body 11 is stitched or otherwise attached to said body, at the frame member 13, and said apron at its lower edge is attached to a tubular metallic frame member 21 of substantially the horizontal contour as the frame member 13 and has in its inner side a longitudinal slot 22. The connection between the apron 20 and frame member 21 is, as shown, the same as that of the body 11 and frame member 12, wherein the lower edge portion of the apron 20, which extends into the frame member 21 through its slot 22, is folded around a flexible core 23 in said member 21 and is secured thereto by stitches 24 or other fastening means 25.

Preferably each frame member 12—13 and 21 is formed from two duplicate metallic tube sections of such gauge as to keep their form under the load they must sustain but at the same time having such flexibility as to produce an easy riding body. The ends of these tube sections forming each frame member 12—13 and 21 are rigidly connected by coupling sleeves or other fastening means 26 that do not obstruct the slots 14, 15 and 21 in the respective frame members 12—13 and 21. Manila rope or other similar material may be used in forming the cores 16—18 and 23. In the construction of the improved body the 100

cores 16—18 and 23 are first threaded end-wise into the sections of the respective frame members which are primarily straight and thereafter bent to form. The coupling sleeves 25 are then applied to the abutting ends of the sections of the frame members 12—13 and 21 and secured thereto by rivets. Before the sections of the frame members 12—13 and 21 are connected, during the manufacture of the carriage, the ends of the several cores 16, 18 and 23 are connected by any suitable means. Obviously the body 11 and apron 20 are suspended from the frame member 12 and the frame members 13 and 21 hold 10 said body and apron taut. From the above description it is evident that each frame member 12—13 and 21 and each core 16, 18 and 23 is, in a broad sense, endless.

Within the body 11 is an inclined back support 26 of fabric or other flexible material and the lower edge portion of which is sewed or otherwise secured to the bottom of said body rearward of the longitudinal center thereof. A strap 27 is sewed to the upper edge portion of the back support 26 and has on its ends hooks 28 adapted to be inserted through any one pair of transversely aligned longitudinally spaced holes 29 formed in the top of the frame member 12 (see Figs. 4 and 5). Obviously, by adjusting the hooks 28 in different transversely aligned pairs of holes 29 the inclination of the back support 26 may be varied at will. By releasing the hooks 28 from the frame member 12 35 the back support 26 may be laid flat on the bottom of the body 11 and under the bedding therein.

The body 11 is removably and yieldingly suspended at each end from the body supports 10 for universal movement by a pair of connectors each of which includes an apertured plate 30 and a short coiled spring 31. Said apertured plates 30 are detachably secured to the body support 10 by being removably applied to upstanding headed studs 31 on said body supports. The springs 32 which extend horizontally and transversely of the body 11 have their intermediate portions secured to said plates by folding said plates therearound and their ends are anchored by short bolts to outwardly and downwardly projecting lugs 33 formed with the coupling sleeves 25 for the sections of the frame member 12. The suspension of the body 11 by the short horizontal springs 32 permits the use of relatively heavy springs and the universal movements thereof will be sufficient to give the body 11 the desired spring action.

60 A pair of stabilizers are provided for cushioning the lateral and longitudinal movements of the body 11 in respect to the chassis 8. As shown, there is one of these stabilizers at each side of the body 11 and each thereof comprises a coil spring 34 intermediately and

detachably secured by a hook-like clip 35 to the respective side of the frame member 21 at the longitudinal center thereof. The end portions of the springs 34 are in diverging relation in respect to the clips 35 and have their ends secured at 36 to the underlying side bars 9. (See Fig. 1). By reference to Fig. 3 it will be noted that the clip 35 is attached to the frame member 21 by being hooked thereover. The stabilizing spring 34 also assist the frame members 13 and 21 in holding the body 11 and apron 20 taut. To remove the body 11 from the chassis 8, it is only necessary to release the clips 35 from the frame member 21 and the plates 30 from the studs 31.

70 Pliable cover flaps 37 are secured to the lugs 33 close to the respective coupling sleeves 25, overlie said lugs, springs 32 and the portions of the plates 30 to which said springs are attached and afford displaceable covers therefor. The above described body when not in use may be folded into compact form and is of light weight.

75 What I claim is:

1. A collapsible body of the class described 90 having an upper marginal frame member, and a flexible intermediate back member attached at its lower edge in respect to the body and having at its upper edge a pair of hooks adapted to be inserted through any one pair of a multiplicity of longitudinally spaced holes in the frame member for detachably securing the back member to the frame member at different longitudinally spaced 95 points to vary the inclination of the back member.

2. A collapsible body of the class described 100 having on its bottom a depending flexible apron which extends completely around the body, and an endless frame member 105 extending completely around the bottom of the apron and supported entirely thereby with freedom to permit the apron to be collapsed with the body resting on the frame member.

3. A collapsible body of the class described 110 having on its bottom a depending flexible apron which extends completely around the body, a tubular frame member extending completely around the bottom of the apron and having a continuous longitudinal slot, and a core in the frame member to which the apron is attached through the slot.

4. The combination with a chassis, of a 115 collapsible body suspended from the chassis and having on its bottom a depending flexible apron which extends completely around the body, a frame member extending completely around the bottom of the apron and suspended entirely therefrom, and spring stabilizing means connecting the frame member to the chassis and holding the flexible apron taut.

5. The combination with a chassis having 120 a pair of substantially parallel side mem-

bers, of a collapsible body, means suspending the body from the chassis, said body having at its bottom a depending flexible apron which extends completely around the body, a frame member extending completely around the bottom of the apron and suspended entirely therefrom, and a coiled spring on each side of the chassis attached at its ends to the respective side member of the chassis and attached at its intermediate portion to the respective side of the frame member.

6. A collapsible body of the class described having a continuous tubular frame member provided with a continuous longitudinal slot, and a core in said member, the sides and ends of the body being continuous and attached at their upper edge portions through said slot to the core.

7. The structure defined in claim 6 in which the frame member comprises half sections connected by couplings.

8. The structure defined in claim 6 in which the frame member comprises half sections connected by couplings, the joints between the half sections being at the ends of the body, and which structure further includes body suspending means attached to the couplings.

9. A collapsible body of the class described having a frame comprising upper and lower tubular members, each of said members being continuous and having a continuous longitudinal slot, and a core in each of said members, the sides and ends of the body being continuous and having their upper and lower edge portions attached through the slots to the cores in the upper and lower frame members, respectively.

In testimony whereof I affix my signature.
